GEORGE HENRY WHEARY, OF RACINE, WISCONSIN.

TRUNK-TRAY CONSTRUCTION.

1,162,716.

Specification of Letters Patent.

Patented Nov. 30, 1915.

Application filed June 11, 1914. Serial No. 844,394.

To all whom it may concern:

Be it known that I, GEORGE H. WHEARY, a citizen of the United States, and resident of Racine, in the county of Racine and State

5 of Wisconsin, have invented new and useful Improvements in Trunk-Tray Construction, of which the following is a description, reference being had to the accompanying drawings, which are a part of this specification.

10 This invention relates to improvements in trunk tray construction.

Trunks of the better class are now usually formed with rounded edges to provide greater strength and to present an ornate 15 appearance. This construction forms inner angular corner edge portions and the trays provided with these trunks were also formed with angular corner edge portions in order to fit the tray space and to rest upon the 20 tray supporting ledges mounted within the trunk. As the trays are formed of very thin light weight lumber or other material, it was necessary to form the angular corners of vertically-extending corner strips which were 25 nailed and glued to the end, side and bottom portions of the tray. The ends of the tray pieces were cut at different angles to join the corner strips and required the services 30 of skilled men to cut and fit the pieces together and nail through the corner strips and edgewise into the other pieces. It was also necessary to incline the upper half portion of the front side board of the tray inwardly so that the front depending cover 35 flange would clear the tray in swinging to open or closed position. This angular relation of the different parts also required careful work in fitting the parts together. This construction materially increased the 40 cost of the trunk as the parts were usually cut and fitted by hand. Furthermore, the trays were not as strong as desired owing to the multiplicity of small parts.

45 It is one of the objects of the present invention to overcome the before mentioned objectionable features and provide a trunk tray construction of rectangular form which will properly fit within the tray space of a trunk and rest upon the supporting ledges 50 of the trunk.

A further object of the invention is to provide a trunk tray construction in which all 55 of the pieces of material forming the tray are of right-angled form and may be easily cut on a standard sawing machine and the

parts, when cut, may be glued and nailed together on a standard nailing machine, thus materially decreasing the cost of manufacture.

A further object of the invention is to 60 provide a trunk tray construction in which the tray is provided with means for guiding the tray into the trunk and which means also serves as guards for preventing the outer surfaces of the tray from becoming 65 marred by rubbing against the vertical walls of the trunk.

A further object of the invention is to provide a trunk tray construction in which the tray is reinforced by strips of material which 70 are tied together by corner members which serve to reinforce the whole tray.

A further object of the invention is to provide a trunk tray which is of simple construction, is strong and durable and is well 75 adapted for the purpose desired.

With the above and other objects in view, the invention consists of the improved trunk tray construction and its parts and combinations as set forth in the claims and all 80 equivalents thereof.

In the accompanying drawing in which the same reference characters indicate the same parts in all of the views: Figure 1 is a top view of a trunk provided with the improved tray construction, parts being broken away to show interior construction; Fig. 2 is a transverse sectional view taken on line 2—2 of Fig. 1; Fig. 3 is a vertical sectional detail view thereof taken on line 3—3 of 90 Fig. 2; Fig. 4 is an enlarged top detail view of one corner portion of the tray, and Fig. 5 is a detail view of a modified form of corner member.

Referring to the drawing the numeral 8 95 indicates the body portion of a trunk, 9 the cover thereof and 10 and 10' the improved trays mounted therein. The trays are of rectangular form and the side and end walls 11, 11', 12 and 12' extend in vertical lines so 100 that all corner and edge joints are formed at right angles and may be easily cut and fastened together on ordinary machines for that purpose. As the trays are substantially of similar construction, it is thought 105 that a detail description of one tray will suffice and the upper tray will, therefore, only be described in detail and the similar parts of the lower tray will be indicated by similar numerals plus prime marks.

The outer horizontal contour of the upper tray is of less size than the inner portion of the trunk into which it extends to permit the cover to clear the front portion thereof, and 5 reinforcing strips 13 fastened to and extending around the medial portion of the tray serve to fill the greater part of the rectangular space between the tray and the trunk body and to also reinforce the tray. The 10 right-angled end portions 14 of the strips terminate short of the corners of the tray and are connected together by corner members 15 which extend around the said corners and overlap the end portions of the reinforcing strips. These corner members are of 15 right angular form and their legs 16 are provided with side flanges 17 which extend over the opposite side portions of the reinforcing strips. The legs 16 of the corner members are secured to the side and end portions of the legs of the corner members and through the reinforcing strips and also through the vertical walls of the tray. The 20 corner portions 19 of the corner members extend diagonally or at forty-five degree angles with relation to their right-angled legs 16 and just clear the corner portions of the tray engaged by said corner members. This diagonal angular corner construction of the 25 corner members accommodates the tray to the inner diagonal corner contour of the body portion of the trunk.

The tray is guided into the body portion of the trunk and the side and end portions 30 of the tray are guarded and protected by rounded bosses or protuberances 20 which are bulged outwardly from the legs 16 of the corner members. These rounded bosses project outwardly a sufficient distance to engage 35 the inner surfaces of the side and end walls of the body portion of the trunk and hold the tray against lateral movement, and the rounded form of the bosses guide the tray into proper position within the body portion 40 of the trunk.

In the lower tray the reinforcing strips 13' and the corner members 15' are positioned 45 near the upper edge of the tray. The end strips of the lower tray engage and rest upon supporting strips 21 extending across and secured to the trunk ends. These strips 21 support the lower tray and also the upper tray which rests upon the upper edge portion 50 of the lower tray and projects out of the body of the trunk and is overlapped by the trunk cover.

In the modified form of corner member shown in Fig. 5, the side flanges 17' of the legs are joined together by diagonally extending corner flange portions 22 which 55 serve to reinforce said members to a considerable extent. In using this form of the member the diagonally extending corner flange portions are driven into the corner 60 portions of the tray until the legs of the said

members rest upon the end portions of the reinforcing strips. The members are then fastened in the same manner before described with relation to the principal form.

From the foregoing description it will be 70 seen that the trunk tray construction provides a tray of rectangular form which is of very simple construction and is adapted to fit into a trunk of the round corner type.

What I claim as my invention is:

1. A trunk tray construction, comprising a tray member of rectangular form having reinforcing strips extending horizontally around the vertical walls thereof, the end portions of said strips terminating at points inside of planes extending diagonally to and across the vertical corner edges of the tray.

2. A trunk tray construction, comprising a tray member of rectangular form having reinforcing strips extending horizontally around the vertical walls thereof, the end portions of said strips terminating at points inside of planes extending diagonally to and across the vertical corner edges of the tray, 85 and means connecting the adjacent ends of the reinforcing strips together.

3. A trunk tray construction, comprising a tray member of rectangular form having reinforcing strips extending horizontally around the vertical walls thereof, the end portions of said strips terminating at points inside of planes extending diagonally to and across the vertical corner edges of the tray, 95 and angular corner members connecting the adjacent end portions of the reinforcing strips together and having vertically-extending flat corner portions which extend across the vertical corner edges of the tray.

4. A trunk tray construction, comprising a tray member of rectangular form having reinforcing strips extending horizontally around the vertical walls thereof, the end portions of said strips terminating at points inside of planes extending diagonally to and across the vertical corner edges of the tray, 105 and angular corner members connecting the adjacent end portions of the reinforcing strips together and having vertically-extending flat corner portions which extend across the vertical corner edges of the tray, 110 said corner member provided with guard portions projecting outwardly therefrom.

5. A trunk tray construction, comprising a tray member of rectangular form, reinforcing strips mounted on the outer sides of the vertical walls of the tray and extending horizontally therearound and terminating at points short of the corners of the tray, and angled corner members having 115 flanged legs which overlap the end portions of the strips, the corner portions of said corner members being flat and extending in planes approximately forty-five degree angles from the legs of said corner member, 120 125 130

the legs of said corner member having rounded bosses projecting outwardly therefrom.

6. The combination with a trunk of the 5 rounded corner type of a tray therefor comprising a tray member of rectangular form mounted within said trunk and being of less size than the trunk to form side and end spaces between the tray and the trunk, reinforcing strips mounted on the side and end portions of the tray and terminating at points short of the corners of the tray, said strips partly filling the side and end spaces between the tray and the trunk, angled corner members having flanged legs which 10 overlap the adjacent end portions of the strips, the corner portions of said corner members being flat and extending in planes approximately forty-five degree angles from the legs of said corner member, the legs of 15 said corner member having rounded bosses projecting outwardly therefrom which guide the tray into the trunk and engage and hold the tray in spaced relation from 20 the side and end walls of the trunks, and securing means extending through the corner legs and the strips and the tray.

7. The combination with a trunk having inner vertical diagonal corners of a tray

therefor, comprising a tray member of rectangular form having parallel end and side walls, the tray being of less size than the trunk so that the corner portions of the tray will just clear the diagonal corners of the trunk, reinforcing strips mounted on the 30 side and end walls of the tray and terminating at points short of the tray corners, and corner members having diagonal corner portions connecting the adjacent ends of the reinforcing strips together and to the tray, 35 the said corner members having rounded outwardly projecting bosses positioned to engage the inner surfaces of the side and end walls of the trunk.

8. A trunk tray construction, comprising 40 a tray member of rectangular form having horizontally extending reinforcing supporting strips mounted on the outer side and end walls thereof which terminate at the 45 corner portions of the tray in a form to permit the tray to be mounted within a trunk having inner diagonally extending corners.

In testimony whereof, I affix my signature, in presence of two witnesses.

GEORGE HENRY WHEARY.
